UNITED STATES PATENT OFFICE

CHARLES LEONARD WOODS, OF ALTON, ILLINOIS

BOAT

Application filed April 23, 1931. Serial No. 532,330.

My invention relates to boats, more particularly to boats of the amphibian type, and it consists in the constructions, combinations, and arrangements herein shown and described.

A primary purpose of my invention is to provide a boat which will have means for getting off the ground if unfortunate enough to get aground in shallow water, that will be able to navigate shallow water, and that will be able to go to and from bodies of water.

A further object of my invention is to provide a boat of the type described that is able to raise its hull above water so that the same may be cleaned, repainted, repaired or inspected while the boat is afloat, thus avoiding the expense of going to dry dock or onto marine ways.

A still further object of my invention is to provide a boat having very great stability, thus enabling the same to proceed under power in heavy weather.

A yet further object of my invention is to provide a device of the type described which has few parts, is simple to manufacture, and does not get out of order easily.

Other objects and advantages will appear as the specification proceeds, and the invention will be more particularly defined in the appended claims.

My device is illustrated in the accompanying drawings forming a part of this application, in which

Figure 1 is an elevational view of my invention,

Figure 2 is a longitudinal sectional view of my invention with parts thereof shown in elevation,

Figure 3 is an end elevational view of a part of my invention with the parts in one operative position,

Figure 4 is a similar view with the parts in another operative position,

Figure 5 is a fragmentary detailed view of a portion of the device, and

Figure 6 is a partly schematic and partly detail view of another portion of the device.

In carrying out my invention, I make use of an ordinary boat hull 1, equipped with an engine, 2, or other suitable power means, or

adapted for manual propulsion in the case of small boats of this type which may be operated by hand without any engines whatsoever.

This boat hull, 1, on either side thereof, is equipped with a land and sea propulsion means, generally indicated at 3, each of said means consisting of a pivotally mounted frame, 4, swivelled as indicated at 5, to the side of the boat, and swivelly mounting at its opposite end a frame, 6. This frame, 4, consists of the angularly formed side members, 7, having a bracing bar, 8, extending therebetween. It supports between its side arms, 7, a rotatable hollow hermetically sealed drum, 9, of heavy construction having on its periphery heavy paddle blades, 10, adapted to support the drum when brought into contact with the land, or to propel the boat through water or carry it over the land when rotated.

For raising and lowering the drums, 9, for raising the boat above the water, as shown most clearly in Figure 2, as well as for raising the boat to enable the same to travel over land, and for propelling the boat through the water in a most efficient manner, the frame members, 6, on each side, which in this embodiment each consist of a pair of side arms, 11, with a bracing arm, 12, are each connected to a hoist, comprising the frame member, 13, secured to the side of the boat as indicated at 14 and 15, and having a bracing arm, 16, between the arm members, 17, thereof. This frame member, 13, supports between its arm members, 17, a drum hoisting mechanism, 18, which may be of any suitable construction, but which is shown in this embodiment as consisting of a rotatable drum member, 19, having a manual means, 20, for the rotation thereof, and a pawl and ratchet mechanism shown at 21 and 22, for securing the drum in a desired position. The bracing arm, 16, of the frame is equipped with a pulley, 23, mounted as shown at 24. About the pulley and the drum the cable, 25, is passed, the ends of said cable being connected to the frame member, 6, as shown at 26 and 27. It

is obvious from this description that rotation of the hoisting drum will bring about elevation and depression of the drum members, 9.

For rotating the drums for travel both on water and over land, the axles, 28, thereof are equipped with sprockets, 29, geared to the sprockets, 30, by means of chains, 31, which 5 sprockets, 30, are mounted on the hollow driving shaft, 32, which bearingly supports the shafts, 5, pivotally supporting the frames, 4. These hollow driving shafts are driven by the motor, 2, through the geared connection, 33. 10 A clutch, 34, enables the operator to apply or withdraw the power as desired.

The shaft, 32, is rotated in one direction by gears, 35 and 36, which are moved into engagement by means of clutch lever, 37, sliding 15 the gear, 35, into mesh with gear, 36, the gear 35, being splined or keyed on shaft, 32. It is rotated in the opposite direction by means of inter-engagement between gears, 36 and 38, gear 38 being similarly splined or keyed on shaft, 32, and operated to its positions by 20 means of clutch lever, 39.

For enabling the operator to drive one of the drums while the other remains stationary, clutches, 39a and 39b, are provided between 25 each of said drums and the gears, 35 and 38, respectively. It can readily be understood that either of the drums can be thrown out of connection with the driving means by operation of these clutches. The motor is equipped with 30 a rheostat, 39c, for controlling the speed thereof in a well known manner.

For stabilizing the boat when the same is elevated above the water by means of the depression of the drums, 9, I suspend at either 35 end of said boat buckets, 40, which will prevent tilting motions of the boat about the drums in a manner easily understood.

From the foregoing description, the use 40 and operation of my device is easily understood. When the operator desires to utilize the invention as a boat, he simply elevates the drums by means of the hoisting apparatus and fixes the same in a desired position with the pawl and ratchet device. It is noted 45 that this pawl and ratchet device is adapted to prevent motion of the hoist in either direction of rotation. He then operates clutch, 34, and one of the gears, 35 or 38, into engagement with gear, 36, in accordance with which 50 direction he wishes the boat to travel. It can readily be understood that the boat will be propelled by the blades on the drums in the desired direction.

When the operator desires to turn the boat 55 either in the water or upon the land while the boat is in motion either in a forward or backward direction, he simply operates one of the clutches, 39a or 39b, to release either 60 the left or right drum, allowing the other drum to rotate, thus turning the boat. He may control the speed of the boat in either direction by means of the rheostat, 39c.

It is understood that, of course, any suitable 65 conventional transmission control could

be utilized in place of the clutch system shown by applicant.

It is also understood that the drums will act as stabilizing means to keep the boat afloat and to propel it in the proper direction during storms and heavy weather. 70

When the operator desires to elevate the boat above the water for purposes of cleaning the hull of the same or for other operations, he simply depresses the drums by 75 means of rotation of the hoisting means thus raising the boat above the water supported by the drums. The buckets at the end of the boat being filled with water will prevent tilting of the same about the drums. 80

When the operator desires to use the device as a land vehicle, he need simply operate the hoist to lower the drums as in the case of elevating the boat above the water and set the drums in motion in the desired direction 85 by means of the gears, 35, 36, and 38, and the clutch, 34. Of course, during this operation, additional supporting means must be supplied for either end of the boat to prevent the same from dragging. This can easily be 90 taken care of by attaching the same to another vehicle or using an additional carriage (not shown) under either end.

It is understood that in the case of large boats a power hoist might be utilized without 95 deviating from my invention. It is further understood that if desired the drums may be driven by a separate power means to enable the operator to utilize the same by moving one or the other for steering of the boat or 100 vehicle.

It is thus seen that I have provided a boat which is adapted to travel on land or navigate on sea and which is further adapted to 105 elevate itself above the sea when desired.

It is further seen that I have provided a boat that is adapted for stable operation during heavy weather, that can get off the ground if unfortunate enough to get aground in shallow water, and raise itself up on the shore 110 on its own power when necessary.

What I desire to claim and secure by Letters Patent is:

1. A boat, comprising a hull, power means positioned in said hull, rotatable drums on either side of said hull, propulsion blades on said drums, pivotal arms supporting said drums, and means for oscillating said pivotal arms to depress and elevate said drums for raising and lowering said boat, consisting of members pivotally mounted to said arms, hoisting frames secured to the hull, drums secured to said hoisting frames, pulleys secured to said hoisting frames, endless flexible members secured at their ends to said pivotally mounted members and trained about their respective pulleys, and drums, means for rotating said drums, and means for securing said drums in a desired position. 115 120 125

2. A boat, comprising a hull, drums posi- 130

tioned on either side of said hull and having propulsion blades thereon, pivotally mounted arms for mounting said drums, means for rotating said drums for propelling the boat,
5 and means for raising and lowering said drums to raise and lower the hull relative to the water, consisting of a hoist pivotally related to the ends of said arms, and pawl and ratchet means associated with said hoist
10 for securing the same in a desired position.

3. A boat, comprising a hull, drums positioned on either side of said hull, means for raising and lowering said drums to raise and lower the hull, and buckets connected to
15 either end of said hull to prevent tilting of said boat about said drums when said hull is in the elevated position.

CHARLES LEONARD WOODS.
